(57) **CLAIM**

The ornamental design for a multiple facet gemstone, as shown.

DESCRIPTION

FIG. 1 is a top view of a multiple facet gemstone showing my new design;

FIG. 2 is a bottom view thereof;

FIG. 3 is a front side view thereof;

FIG. 4 is a rear and right corner view thereof, the rear and left corner view being identical thereto;

FIG. 5 is a front and right corner view thereof, the left and right corner view being the mirror image thereof;

FIG. 6 is a perspective view thereof;

FIG. 7 is a left side view thereof,

FIG. 8 is a top side view thereof, shown in a position of use; and,

FIG. 9 is a bottom view thereof, shown in a position of use. The broken line showing of gemstones in FIGS. 8 and 9 is included for the purpose of illustrating environmental matter and forms no part of the claimed design.
